UNITED STATES PATENT OFFICE.

LIONELLO GANUCCI CANCELLIERI AND ANCHISE CAPPELLETTI, OF FLORENCE, ITALY.

APPARATUS FOR APPLYING CLOSURES.

1,125,466.

Specification of Letters Patent.

Patented Jan. 19, 1915.

Application filed December 30, 1910. Serial No. 600,173.

To all whom it may concern:

Be it known that we, LIONELLO GANUCCI CANCELLIERI, proprietor, and ANCHISE CAPPELLETTI, joiner, subjects of the King of Italy, residing at Florence, Italy, have invented new and useful Improvements in Apparatus for Applying Closures, of which the following is a specification.

This invention relates to a system devised by the applicants with the object of increasing the initial surface of metallic sheets and plates by submitting them to very great lateral strains of distention and traction thereby by distorting them on their turned up edge, or at the same time cumulating the two effects.

This invention is carried into practice by means of a distorter of metallic sheets and plates, that is to say of apparatus which constitutes part of the invention forming the subject of the present application.

The method of carrying out and commercially applying this fundamental idea in its most complex form, that is to say when the distorting apparatus is mounted on a support capable of enabling the closing of bottles, flasks, small vases, etc., to be effected with facility as illustrated in the accompanying drawings, in which—

Figure 1 is a view in side elevation of the device mounted upon a support; Fig. 2 is a plan view; Fig. 3 is a vertical sectional view thereof; Fig. 4 is a vertical sectional view of the device on an enlarged scale; Fig. 5 is a sectional view taken on the line X—Y of Fig. 4; Fig. 6 is a vertical sectional view of the metallic sealing plate; Fig. 7 is a plan view thereof; Fig. 8 is a sectional view showing the plate in position within the neck of a bottle before expansion; Fig. 9 is a sectional view illustrating the manner of removing the upper portion of the neck of the bottle in which the plate is secured, and Fig. 10 is a sectional view similar to Fig. 8 showing the plate expanded.

In these figures it will be seen that the distorting apparatus (which is represented separately and in detail in Figs. 4 and 5) is fixed by means of two screws *v* to a frame *i*, which in turn is by means of two ears *l* carried on two suitable supports *m*, *m*. The frame terminates on its under side in a circular box *n* which is free on its under side. The upper face *o* of the box is movable longitudinally and slides in the box itself.

The spring *p* tends to keep the same raised; and a metallic wire *t*, which is fixed to the face *o* and terminates in a knob *u*, when drawn from the outside, will cause the face *o* to descend; it is with this object that the bottom face *q* of the box is provided with two openings *f* for the emission of air when said movable face descends. So that while the frame *i* serves to support the distorter and maintain the same rigidly, the box *n* insures that a bottle or flask *b*, for example, after it has been applied to the movable face *o* and placed in position, shall be constantly held with force in contact with the lower part of the distorter, provided that the spring *p* is of sufficient strength.

The distorter may be employed even without a support, and it is represented in vertical section in Fig. 4 and in horizontal section on the line *x*—*y* in Fig. 5. It is composed of a hand or fly wheel *c*, in the center *d* of which a shaft *e* of cylindrical form is situated, which in the first place for about a third of its length is enlarged and provided with a screw thread *z*, and is then continued in cylindrical form *y* of much smaller section, and having a perfectly smooth surface. The screw *z* engages an internally screw threaded sleeve *g*, which projects downward and in its lower part contains all the other parts which serve for the extension of the metallic plates, and which from the upper end downward are situated in the following order: A circular washer *h* with a screw threaded edge *r* works in the screw thread of the sleeve, and has a central bore *s* for permitting the passage of the thin shaft *y* of the hand or fly wheel; an open spiral spring *u*, which by exerting a pressure on another washer *x*, also of circular form and with a central opening, but the edge of which is smooth and, consequently, movable in a vertical direction, compels the lower part of the 4 slides 1, 2, 3, and 4 to remain united, such slides being situated beneath and leaving between them a central opening *5*, into which the axis *y* of the fly wheel may be introduced, such opening being for the greater part of its length cylindrical and at the lower part conical.

By turning the fly wheel *c* from left to right, the screw *z* is advanced into screw threaded sleeve *g*, and the axis *y* of the fly wheel descends downward into the central opening *5* left between the slides 1, 2, 3, and 4. After its arrival there, seeing that

such opening, becoming conical, narrows, it is caused to bear on the internal walls of the slides and compels the latter to separate one from the other, in spite of the opposition 5 exerted by the spiral spring.

If it is imagined that before imparting the initial movement to the fly wheel the lower parts of the slides have been caused to slide gently into a metallic circular plate 10 6 provided with an edge 7 bent up at a right angle, similar to a box lid or a capsule as is illustrated, in vertical section in Fig. 6, and, in plan in Fig. 7, it will be readily understood that at the termination of the 15 movement, said plate, in consequence of the action exerted by the slides, will be inevitably elongated on its flat surface and even distorted at its edge, and that according to the form of the slides. If it is supposed, 20 finally, that this action is exerted during the time that the plate, or capsule has been previously inserted in the circular groove 8 existing in the neck of a bottle, as is represented in Fig. 8, in which 9 is the space 25 occupied by the stopper of cork, or glass, or by a drip counter, so that the edge of the plate, by being distorted, is forced into the circular groove 8, it is evident that this system of distention of metallic plates can be 30 converted into a system of closing of general application and especially suitable for glass receptacles (such as bottles, flasks, jars, etc.) Finally, it is necessary to point out that the 35 slides instead of being 4 in number may be 5 of any other number, and may have any suitable form for the distention and distortion of any form of plates, and that when the closed receptacles are of glass they may be readily opened by breaking or removing 40 45 by means of a slight blow that portion of the glass in which the metallic plate has become inclosed, as will be seen in Fig. 9, while Fig. 10 represents the closed receptacle before the removal of the part 10 45 which incloses the metallic plate.

What we claim as our invention, and desire to secure by Letters Patent, is—

1. In apparatus for expanding a metallic plate, in combination, a hollow casing 50 provided with an inwardly extending flange at its lower end, a plurality of members engaging said flange and adapted to rock thereon, means within said casing normally extending to rock said members in one direc-

tion, and means for rocking said members 55 in the opposite direction.

2. In apparatus for expanding a metallic plate, in combination, a hollow casing provided with an inwardly extending flange at its lower end and provided with an internal 60 thread at its upper end, a plurality of members engaging said flange and adapted to rock thereon, said members having portions extending in an upward direction within said casing, a flat washer engaging the 65 threaded portion of said casing, a washer movably positioned within said casing and engaging the upwardly extending portions of said members, a spring interposed between said washers, whereby said members 70 will normally be urged to rock in one direction, and means for rocking said members in the opposite direction.

3. In apparatus for expanding a metallic plate, in combination, a hollow casing provided with an inwardly extending flange at its lower end, a plurality of extending members pivotally supported upon the inner edge of said flange and adapted to rock with respect thereto, said members having downwardly extending normally converging arms, and means for rocking said members about their pivotal points of support to cause said arms to move outward. 75

4. In apparatus for expanding a metallic 80 plate, in combination, a hollow casing provided with an inwardly extending flange at its lower end, a plurality of extending members pivotally supported upon the inner edge 90 of said flange and adapted to rock with respect thereto, said members being provided with downwardly extending converging arms and with upwardly extending diverging arms, means engaging said diverging arms normally tending to rock said members 95 about their pivots in one direction and means engaging said converging arms adapted to rock said members about their pivots in opposite direction.

In testimony whereof we have signed our 100 names to this specification in the presence of two subscribing witnesses.
